Primary Examiner — Philip S Hyder*Assistant Examiner* — Keith Frank(74) *Attorney, Agent, or Firm* — Saidman DesignLaw Group, LLC(57) **CLAIM**

The ornamental design for a capsule, as shown and described.

DESCRIPTION

FIG. 1 is a front perspective view of a capsule showing my new design;

FIG. 2 is a rear perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is bottom view thereof.

The drawings include surface shading lines which represent contour, not surface ornamentation. The dashed broken lines represent structure or features that form no part of the claimed design. The dot-dash broken lines represent boundaries of the claimed design; the boundaries themselves form no part of the claimed design.
